UNITED STATES PATENT OFFICE.

KATE M. GUINIS AND SPYROS D. VAMVAS, OF JACKSONVILLE, FLORIDA.

DESIGN FOR A HEAD ORNAMENT.

47,996.

Specification for Design.

Patented Oct. 19, 1915.

Application filed July 28, 1915. Serial No. 42,429. Term of patent 7 years.

To all whom it may concern:

Be it known that we, KATE M. GUINIS, a subject of the King of Greece, and SPYROS D. VAMVAS, a citizen of the United States, residing at Jacksonville, in the county of Duval and State of Florida, have invented a new, original, and ornamental Design for Head Ornament, of which the following is a specification, reference being had to the accompanying drawing, forming part thereof.

The figure is a view in elevation of the head ornament, showing our new design.

We claim:

The ornamental design for a head ornament, as shown.

KATE M. GUINIS.
SPYROS D. VAMVAS.
